UNITED STATES PATENT OFFICE.

KARL BUCHBERGER, OF ALBANY, NEW YORK.

PROPELLING DEVICE FOR BALLOONS AND FLYING-MACHINES.

No. 907,312.

Specification of Letters Patent. Patented Dec. 22, 1908.

Application filed April 24, 1908. Serial No. 428,024.

To all whom it may concern:

Be it known that I, KARL BUCHBERGER, a subject of the Emperor of Austria-Hungary, and a resident of Albany, county of Albany, State of New York, have invented 5 certain new and useful Improvements in Propelling Devices for Balloons and Flying-Machines, of which the following is a specification.

The present invention pertains to propelling apparatus for balloons or flying machines and consists in the construction, arrangement and combination of parts as will be hereinafter fully specified.

To make my invention more clear the same is illustrated in the accompanying drawings in which similar reference numerals denote corresponding parts and in which

Figure 1 is an elevation of my apparatus; Fig. 2 is a vertical section thereof, the wings being broken away; Fig. 3 is a longitudinal section of one end of the apparatus, and Fig. 4 a plan view thereof.

In the drawings 1 denotes the frame which may be either attached to a balloon or be a part of the frame of a heavier-than-air machine. This frame is adapted to carry the propelling device which forms the subject of the present application.

The propelling device consists of two pairs of wings 2, 2' and 3, 3', the wings of each pair being arranged crosswise to each other, and by a spindle 4 are loosely carried by the ends of a rotary shaft 5 journaled in the frame 1.

Rigidly and centrally secured to the frame 1 are ring shaped brackets 6, 6 between which a hollow cylinder 7 is arranged. By means of pins or projections 8 engaging annular grooves 9 in the inner surfaces of the brackets 6, 6, this cylinder is carried by the latter so as to be capable of turning around its longitudinal axis. The shaft 5 is supported in the brackets 6 by ball bearings 10 and loosely extends through the cylinder 7, the inner diameter of which is larger than the diameter of the shaft.

Slidably borne in longitudinal opposite grooves of the shaft 5 are bars 11, 11, to the ends of which chains 12 are attached which engage around and are adapted by the reciprocating movement of the bars 11, 11 to drive sprocket wheels 13 keyed to the spindles 4 of the wings.

The bars 11, 11 are each provided with a projection 14 which are engaged in a cam

shaped groove 15 provided in the inner surface of the cylinder 7 and owing to which, at the rotation of the shaft 5, the bars 11, 11 are caused to reciprocate in longitudinal and a reversed direction to one another. By this reciprocating movement the wings are swung upon themselves while simultaneously revolving with the shaft 5, so that the wings of each pair are caused to intermittently exercise a propelling action.

If it is desired to change the position and the direction of the swinging movement of the wings, all that is necessary is to turn around the cylinder 7 so as to change its position. Normally the cylinder 7 is secured in position by a set screw 16 working in a projection 17 of one of the brackets 6 and engaging notches in the surface of the cylinder. After slackening this set screw the cylinder is released and can be turned upon itself.

18 denotes ball bearings provided in the cam groove to afford easy movement of the projection in the cam groove.

The shaft 1 may carry a pulley 19 for the transmission of movement thereto from a motor 20 suitably arranged on the frame 1.

What I claim and desire to secure by Letters Patent is:

1. The herein described propelling device, comprising a frame, a rotary shaft therein, a pair of wings rotatively borne on each end of said shaft, the wings of each pair being arranged crosswise to one another and adapted to be swung perpendicularly to the said shaft, two diametrically opposed bars longitudinally and slidably borne in said shaft, a sprocket wheel in the center of each pair of wings, a chain engaging around said sprocket wheel and having its ends secured to the ends of the opposite bars, a hollow cylinder rotatively carried by said frame and embracing the shaft, said cylinder having a spiral groove containing a ball bearing, projections on said slide bars engaging said groove, said bars at the rotation of the shaft being caused to reciprocate in a reverse direction to one another and to thereby impart a swinging movement to the wings, substantially as set forth.

2. The herein described propelling device, comprising a frame, a rotary shaft therein, a pair of wings rotatively borne on each end of said shaft, the wings of each pair being arranged crosswise to one another and adapted to be swung perpendicularly to the said

shaft, two diametrically opposed bars longitudinally and slidably borne in said shaft, a sprocket wheel in the center of each pair of wings, a chain engaging around said sprocket wheel and having its ends secured to the ends of the opposite bars, a hollow cylinder rotatively carried by said frame and embracing the shaft, said cylinder having a spiral groove containing a ball bearing, projections on said slidable bars engaging said groove, said bars at the rotation of the shaft being caused to reciprocate in a re-

verse direction to one another and to thereby impart a swinging movement to the wings, and means for the adjustment of the cylinder to allow a change in the direction of the swinging movement of the wings, substantially as set forth. 15

Signed at New York this 23 day of April, 1908.

KARL BUCHBERGER.
